UNITED STATES PATENT OFFICE.

GEORGE M. TAYLOR, OF HARTFORD, CONNECTICUT.

DESIGN FOR A TOOL-TRAY.

55,492.

Specification for Design. Patented June 15, 1920.

Application filed December 3, 1919. Serial No. 342,276. Term of patent 14 years.

To all whom it may concern:

Be it known that I, GEORGE M. TAYLOR, a citizen of the United States, residing at Hartford, in the county of Hartford, and State of Connecticut, have invented a certain new, original, and ornamental Design for a Tool-Tray, of which the following is a specification, reference being had to the accompanying drawings, forming part thereof, wherein—

Figure 1 is a plan of a tool tray embodying my new design,

Fig. 2, an edge view of the same, and

Fig. 3, a section of the same on line 3—3 of Fig. 1.

I claim:—

The ornamental design for a tool tray, as shown.

GEORGE M. TAYLOR.
